UNITED STATES PATENT OFFICE.

BENNIE A. TAROMINO, OF NEW BRUNSWICK, NEW JERSEY.

TIME-CONTROLLED LIGHTING SWITCH.

Application filed January 19, 1925. Serial No. 3,472.

This invention relates to improvements in time controlled lighting means and is more particularly adapted to a mechanism for automatically lighting the parking light on an automobile.

One of the important objects of the present invention is to provide a time controlled lighting switch of the above mentioned character, which is adapted to be associated with a clock which is mounted on the automobile in any convenient place whereby a person may set the time at which the switch is to be automatically turned on for lighting the parking light of the automobile.

A further object is to provide a time controlled lighting switch of the above mentioned character wherein the usual alarm operating shaft of a clock mechanism is employed for actuating the switch to turn the same on whereby the circuit to the parking light of an automobile will be automatically completed at a predetermined time, additional means being provided for breaking the circuit whenever it is so desired.

A still further object is to provide a time controlled lighting switch of the above mentioned character, which is simple in construction, inexpensive, strong and durable and further well adapted for the purposes for which it is designated.

Other objects and advantages of this invention will become apparent during the course of the following description.

In the accompanying drawing forming a part of this specification, wherein like numerals designate like parts throughout the same:

Figure 1 is a view partly in section of the switch mechanism embodying my invention.

Figure 2 is a front elevation of the end of the casing showing the manually operated member mounted thereon, and

Figure 3 is a sectional view through the casing and through the rotatable fiber bit.

In the drawing wherein for the purpose of illustration is shown the preferred embodiment of my invention, the numeral 1 designates generally an alarm clock of any well known construction, the same being adapted to be secured on an automobile in any desirable place whereby ready access thereto may be had. The usual alarm actuating shaft or arbor of the clock mechanism is illustrated at 2. A spiral gear 3 is mounted on the shaft or arbor 2 and the purpose

thereof will hereinafter be more fully described. The dial associated with the usual alarm mechanism of the clock is illustrated at 4 and the indicator cooperating therewith is illustrated at 5.

A casing 6 extends outwardly from the side of the clock and is substantially rectangular in cross section as clearly illustrated in Figures 2 and 3. A substantially rectangular shaped block of insulating material such as fiber or the like and indicated by the numeral 7 is disposed within the casing 6 adjacent the outer closed end 8 thereof. The fiber block 7 is provided with an enlarged central opening 9 as clearly illustrated in Figure 3.

Suitable binding posts 10 and 11 extend through the upper and lower portions of the fiber block 7 and the casing 6. Stationary contacts 12 and 13 are associated with the inner opposed ends of the binding posts, the same being arranged in suitable cut out portions provided therefor in the block 7 adjacent the opening 9 so that the inner faces of the stationary contacts will conform to the shape of and lie flush with the face of the opening. The binding post 10 is connected to a suitable source of electric energy designated at 14 by the wire 15. Arranged in the same circuit is the parking lamp 16 and the same is connected to the binding post 11 by the wiring 17. The usual knurled nuts 18 are detachably associated with the outer end of the binding post for the purposes well known in the art.

Extending centrally through the cover or outer end 8 of the casing 6 is the shaft 19. A circular fiber disc 20 is secured on the inner end of the shaft and is adapted for rotation within the opening 9 provided in the fiber block 7 it being understood that the disc 20 is of a diameter less than the diameter of the opening 9. The fiber disc 20 is provided with the central bore 21. A pair of movable contacts 22 and 23 are disposed in the opposite ends of the bore 20. A coil spring 24 is arranged within the central bore 21 between the inner adjacent ends of the contacts 22 and 23 and normally urges the same outwardly so that the same will engage the inner face of the stationary fiber block 7, the same being further adapted for engagement with the stationary contacts 12 and 13 respectively in the manner to be presently apparent.

A drive shaft 25 extends through the side of the clock 1 and the outer end thereof is disposed within the casing 6. A spiral gear 26 is provided on the inner end of the drive shaft 5 and meshes with the spiral gear 3 associated with the shaft or arbor 2. A conical head 27 is formed on the outer end of the drive shaft 25 for frictional engagement with the conical recess 28 formed on the inner face of the disc 20, the coil spring 29 being associated with the outer end of the shaft 25 for normally urging the conical head 27 into engagement with the conical recess 28, a nut 30 being threaded on the threaded portion for adjusting the tension of the coil spring 29. This construction provides what may be termed as a clutch for operatively associating the disc 20 with the drive shaft so that the former may be rotated by the latter at the proper time.

A handle 31 is secured on the outer end of the shaft 19. A pointer 32 is associated with the handle. Suitable indicia is printed on the outer face of the outer end 8 of the casing 25 at predetermined places whereby the pointer 32 cooperates therewith in indicating to a person whether or not the switch mechanism is on or off.

Assuming that the contacts 22 and 23 are out of engagement with the contacts 12 and 13 respectively, whereby the circuit to the parking light 15 is open or broken, the hour or time at which it is desired to light a parking lamp is set by setting the usual indicator 5 at the desired hour on the dial 4 in the usual manner. As soon as the time at which the indicator 5 has been set is reached, the shaft 2 will rotate simultaneously causing movement to be imparted to the drive shaft 25 through the spiral gearing heretofore described and the drive shaft 25 will in turn rotate the disc 20 and the shaft 19 on which the same is supported so as to move the contacts 22 and 23 into engagement with the stationary contacts 12 and 13. This will complete the circuit to the lamp 16 and thereby cause the parking light to be auto-

matically lit. The parking light may be turned off by a person turning the handle 31 to either direction whereby the disc 20 will be rotated and causing the movable contact to be brought out of engagement with the stationary contact. The indicia printed on the outer end 8 of the casing will assist the person in ascertaining whether or not the switch is turned on or off.

It will thus be seen from the foregoing description, that a time controlled lighting switch has been provided for use in connection with the parking light of an automobile which is controlled by the usual alarm shaft of a clock, the simplicity in which my device is constructed renders the same positive and efficient in its operation at all times.

While I have shown the preferred embodiment of my invention, it is to be understood that various changes in the size, shape and arrangement of parts may be resorted to, without departing from the spirit of the invention and the scope of the appended claim.

Having thus described the invention, what I claim is:—

In a switch of the class described a casing, a stationary block of insulating material in said casing, the same being provided with an enlarged central opening, stationary contacts arranged at diametrically opposite points in the stationary block and extending into the opening, a rotatable disc arranged within the central opening of the stationary block, a pair of diametrically opposed contacts carried by the disc and adapted for co-operation with the stationary contacts, and means for effecting the rotation of the disc, said means comprising a drive shaft, a conical head on the outer end thereof, the rear face of the disc having a conical recess formed therein for cooperation with the aforementioned conical head, and a coil spring associated with the shaft for holding the conical head in engagement with the conical recess.

In testimony whereof I affix my signature.

BENNIE A. TAROMINO.
